UNITED STATES PATENT OFFICE.

JAMES E. KERMODE, OF VALLEJO, CALIFORNIA.

COMBINATION RUNNING BOARD, TABLE, AND CONTAINER.

Application filed March 29, 1922. Serial No. 547,704.

To all whom it may concern:

Be it known that I, JAMES E. KERMODE, a citizen of the United States, residing at Vallejo, county of Solano and State of California, have invented new and useful Improvements in Combination Running Boards, Tables, and Containers, of which the following is a specification.

This invention relates to a combination container and table for automobiles, and especially to a device of this character which may become a part of the running board of an automobile.

For camping trips, Sunday outings, and for shopping purposes or the like, automobiles are often equipped with foldable brackets, trunks or other devices in which bundles, camping equipment, etc., may be placed. Such devices are invariably secured on the exterior of a car and are in most instances permanently fastened to the running board, where they form an obstruction when not required, and furthermore usually detract from the usual appearance of the car.

The object of the present invention is to generally overcome the objections referred to; to improve and simplify devices of this character, and particularly to provide a foldable running board which when folded will have the general appearance of an ordinary running board, but when unfolded or extended may either serve as a container or as a table, as will hereinafter be more fully described. Further objects will hereinafter appear.

The invention consists of the parts and the construction, combination and arrangement of parts as hereinafter more fully described and claimed, having reference to the accompanying drawings in which—

Fig. 1 is a perspective view partly broken away, showing one end of the foldable running board, which may serve either as a container, a table, or a running board.

Fig. 2 is a perspective view of the front end of an automobile showing the application of the invention.

Fig. 3 is a plan view of the container partially in section and parts being removed.

Fig. 4 is a central, vertical cross section of the container.

Fig. 5 is an end view of the container showing it extended to serve as a table.

Referring to the drawings in detail, and particularly to Figs. 1 and 2, A indicates the base portion of the container which in this

instance is reinforced along the sides and ends by means of an angle iron as indicated at 2. The base may be constructed of any suitable material, but preferably of sheet iron as a minimum of space is in this manner consumed. The sides of the base section are flanged and turned upwardly as indicated at 3 and 4, and the upper edges of said flanges are turned over to form bearings 5 and 6, in which is journaled a pair of rods 7 and 8. Pivotaly attached to the rod 7 carried by the journal members 5 is a front section 9, and similarly attached to the opposite rod 8 is a rear section 10. Both sections are foldable with relation to the base or bottom section A and may be folded downwardly against the same when the container is to be collapsed as will hereinafter be described.

Formed on the ends of the front section 9 are bearing members as indicated at 11, and extending therethrough are rods 12, on which are pivotally mounted end sections 13. These sections are foldable inwardly against the front section 9 and may be folded together with this end section against the base when the whole structure is collapsed. They are otherwise normally extended when the parts are unfolded by means of coil springs 14 interposed between the bearing sections 11, the front and rear sections 9 and 10 being similarly normally raised about their pivotal mountings by means of coil springs 15 and 16. The rear section 10 is provided with a sliding cover section 17. This cover section forms the top of the running board when the parts are folded, and it also forms a cover for the container when the parts are unfolded as shown in Fig. 4. It furthermore serves as a table when desired as will later be described.

The cover section 17 may be constructed of any suitable material, for instance linoleum, and is reinforced by angle iron secured along its ends and outermost side as indicated at 19 and 18 respectively. The ends of the angle bars 19 terminate in V-shaped notches 20, adapted to engage projections 21 formed on the rod 8, that is the rod 8 is slightly longer than absolutely required and as such projects a sufficient distance to permit the V-notches of the reinforcing ends 19 of the cover to be engaged. The rod 8 thus serves as a stop which limits the downward sliding movement of the cover section 17 with relation to the back section 10. The upper

edge of the back section 10 is reinforced by a rod 22. The ends of this rod project as indicated at 23, and as such enter a slot or guide formed on the inner side of each 5 end section 19. This guide is formed in any suitable manner or as here illustrated by riveting a strip 24 on the inner side thereof, said strip being provided with right-angled end extensions indicated at 25 to 10 limit the upward or outward sliding movement of the cover 17 with relation to the back section.

In actual practice the several parts assume the following position: The end sections 13 are folded inwardly against the front section 9 and as such rest directly against the base or bottom section A. The front section 9 rests directly on top of the end sections, and the rear section 10 when 15 folded will in turn rest upon the front section. The section 17 then forms a cover for the whole and may be secured by a latch or any other suitable locking means. When the parts are folded, the cover forms that 20 portion of the running board upon which the users of the car step when entering or leaving the car. This cover member gives the ordinary appearance of a running board, and as such does not detract from the general 25 appearance of the car, nor does it in any way form an obstruction. If it is desired to use the running board as a table, it is only necessary to release the lock and to pull the cover in a forward direction 30 as indicated in Fig. 5. A pair of supporting legs 30, pivotally secured as at 31 to the inner side of the reinforcing angle iron 18, may then be turned downwardly and as such will form a support for the table. If 35 it is desired to employ the running board as a carrying trunk or container, it is only necessary to raise the cover and the rear section 10 until they assume the vertical position shown in Figs 1 and 4; this position 40 being readily assumed as the tension of the coil springs 16 will materially assist such movement. The front section 9 is then grasped and swung about its pivotal rod 7, which movement is also assisted by the tension 45 of the springs 15. The end sections 13 will automatically swing outwardly as shown in Fig. 1 when the front section is raised and they may here be locked as their inner ends are flanged as at 28 and are received by end channels 26 formed in the 50 rear section 10. When the flanges 28 enter the end channels 26, an interlock is made and accidental release is prevented by providing a pair of pivoted latches such as 55 shown at 29 which has swung downwardly against the end sections thus clamping the same. The front and rear sections 9 and 10 are held in a vertical position, due to the tension of the springs 15 and 16, and also 60 by the end sections 13; a fixed spacing being 65

maintained by the end sections and spreading or further opening of the side sections being prevented by the interlock formed. The container may now be filled with bundles, camping equipment or whatever desired, and the hole may be closed by the cover section 17. To place the cover in position, it is first necessary to grasp the reinforcing edge 18 and to lift the cover vertically until the lower stops 25 engage 70 the projecting ends 23 of the upper reinforcing rod. The cover may then be swung about the projecting ends of said rod, as these will then serve as a hinge, and the cover may thus be swung downwardly over 75 the front and end sections to cover the contents of the container; the cover being here locked if desired by a latch or other securing means of any description, not here shown. 80

The entire structure is exceedingly simple and as sheet iron may be employed throughout, it can readily be seen that the cost of manufacture should be fairly small, and that the space consumed will be almost 85 immaterial, due to the fact that the few parts employed are thin and will fold flatly one on top of the other. The ordinary appearance of the running board will in this manner not be affected as the present device can hardly be detected when the parts are folded. The device as a whole may be quickly collapsed or extended when required and as such should not only serve as a useful adjunct for camping or otherwise traveling, 90 but also for ordinary town shopping and the like. 100

The base section A of the present container may extend from the front mud-guard to the rear mud-guard and as such 105 may be supported by the usual brackets provided for running boards. Again it should be obvious that the present device may extend over a portion of the running board if desired as the structure will in no way be 110 affected whether the length is increased or decreased. Again, while certain features of the present invention are more or less specifically illustrated, I wish it understood that various changes in form and proportion 115 may be resorted to within the scope of the appended claims, similarly that the materials and finish of the several parts employed may be such as the experience and judgment of the manufacturer may dictate 120 or various uses may demand. 125

Having thus described my invention, what I claim and desire to secure by Letters Patent is—

1. A convertible running board for automobiles, comprising a base, a pair of side sections pivotally mounted thereon and foldable relative thereto, end members pivotally connected at one edge to one of said side sections, means for detachably connecting said 130

end members to the other side section, and a cover slidably and pivotally connected to one of said side sections.

2. The combination with the running board of an automobile, of an inner and an outer side section pivotally attached thereto to permit folding downwardly against the running board or vertical positioning of the same, a cover member carried by one of said side sections, and means permitting sliding and pivotal movement of said cover section with relation to the member carrying the same.

3. The combination with the running board of an automobile, of an inner and an outer side section pivotally attached and foldable with relation thereto, a pair of end members pivotally attached to the front section and adapted to be detachably connected to the other side section, and a cover carried by the inner side section and slidably and pivotally movable with relation thereto.

4. The combination with a running board of the character described, of an inner side section pivotally attached and foldable with relation to the running board, a reinforcing rod in the upper end of said side section, said rod projecting from the respective ends of the side sections, a cover member, the

sides and ends of which are reinforced, and 30 guide members on the inner sides of the reinforcing end sections into which the ends of the rod project and which permit sliding and pivotal movement of the cover with relation to the inner section.

5. The combination with a running board of the character described, of an inner side section pivotally attached and foldable with relation to the running board, a reinforcing rod in the upper end of said side section, 40 said rod projecting from the respective ends of the side sections, a cover member, the sides and ends of which are reinforced, 45 guide members on the inner sides of the reinforcing end sections into which the ends of the rod project and which permit sliding and pivotal movement of the cover with relation to the inner section, a front section pivotally attached and foldable with relation to the running board, a pair of end sections pivotally attached to the front section, channels formed at each end of the inner section, flanges formed on the end sections adapted to enter said channels, and a pair of latches carried by the inner side section 50 movable to and away from the end sections.

JAMES E. KERMODE.
